[57] CLAIM

The ornamental design for a vending machine housing, as shown and described.

DESCRIPTION

FIG. 1 is a front, right side, top perspective view of a vending machine housing, showing my new design;

FIG. 2 is a right side elevational view thereof;

FIG. 3 is a front side elevational view thereof;

FIG. 4 is a left side elevational view thereof;

FIG. 5 is a rear side elevational view thereof;

FIG. 6 is a top plan view thereof;

FIG. 7 is a bottom plan view thereof;

FIG. 8 is a cross-sectional view taken along the line VIII—VIII from FIG. 5;

FIG. 9 is a cross-sectional view taken along the line IX—IX from FIG. 5;

FIG. 10 is a front, right-side, top perspective view of a second embodiment of the housing as disclosed in FIG. 1;

FIG. 11 is a right side elevational view of FIG. 10;

FIG. 12 is a front side elevational view of FIG. 10;

FIG. 13 is a left side elevational view of FIG. 10;

FIG. 14 is a rear side elevational view of FIG. 10;

FIG. 15 is a top plan view of FIG. 10;

FIG. 16 is a bottom plan view of FIG. 10; and,

FIG. 17 is a cross-sectional view taken along the line XVII—XVII from FIG. 14.

The broken away sections are due to the indeterminate length of the claimed design.
